Hart E. Delvin,

UNITED STATES PATENT OFFICE.

HART E. DELVIN, OF NEW YORK, N. Y.

NUMERAL-WHEEL-RESETTING DEVICE.

1,112,895.

Specification of Letters Patent.

Patented Oct. 6, 1914.

Application filed July 22, 1912. Serial No. 710,349.

To all whom it may concern:

Be it known that I, HART E. DELVIN, a citizen of the United States, and a resident of New York, in the county of New York and State of New York, have invented certain new and useful Improvements in Numeral-Wheel-Resetting Devices, of which the following is a specification.

This invention relates to improvements 10 in registering devices and particularly to that class in which a row of numeral wheels are displayed showing the sum total arrived at by adding or subtracting mechanisms combined therewith.

15 The object of the invention is to enable an operator to set at zero or initial position, the numeral wheels in such mechanisms, by novel and convenient means, expeditiously and positively.

20 This object is attained by the instrumentation hereinafter described and shown in the accompanying drawings, in which:—

Figure 1 is a partial plan view of a registering mechanism, the cover being removed. Fig. 2 is an end view of the same, the side plate being removed to show the general arrangement and relation of parts. Fig. 3 is a perspective view of the cam washer operating the engaging means.

25 Fig. 4 is a similar perspective view of a numeral wheel and its drive gear. Fig. 5 is a like perspective view of the ratchet and its shaft. Fig. 6 is a perspective view of the sleeve and shaft upon which the numeral wheels are mounted. Fig. 7 is a similar view showing the arrangements of the operative parts involved, and, Fig. 8 is a transverse sectional view, taken on line 8—8 of Fig. 7.

30 The numeral wheels or disks 10, which are free to revolve in either direction, have on their periphery the numerals 0 to 9 inclusive and are arranged side by side with a gear wheel 11 secured as a unit to each 45 numeral disk, the gear wheel transmitting motion from actuating mechanism not being shown. These numeral wheels are mounted so as to revolve freely upon the sleeve 20, partially enveloping the shaft 12,

50 near one end of which is a fixed collar 13, having a groove 14 adapted to act as the bearing for the rod 15, which is rigidly connected with the curved plate 16 normally resting on the shaft 12 and provided at its 55 outer front edge with a series of projections 17 arranged so that each projection is in

register with an internal tooth 18 formed in the enlarged bore 18' of the gear 11. The teeth 18 are arranged with respect to the numerals so that when the entire row 60 of ciphers appear in alinement the several teeth 18 will also be in alinement and will be in position to engage with the projections 17 of the plate. The opposite end of the plate 16 is revolvably secured in the gear 65 19 which transmits motion to it. The plate 16 is adapted to operate within an open space or groove 21 formed in the sleeve 20 and is driven by the gear 19 rotatable within a recess formed in the inner side of the 70 frame plate 25; at the opposite side and in the corresponding frame 26 is rigidly secured a thin collar or washer 27 through which the shaft 12 extends and which is provided with an annular opening 28 having a recess or depression 29 acting as an 75 internal cam adapted to receive the end of a lever 30 pressed against the said recess by means of the spring 31 and so arranged that when the lever is disposed within the 80 recess the numeral wheels and gears are free to revolve on the surface of the sleeve 29 over the plate 16 and clear of the teeth 17, the gears being rotated as is usual.

Meshing with the gear 19 is a spur gear 36 85 secured to the shaft 35 which has rigidly upon it the ratchet 37 actuated by the pawl 38 having the spring 39 and being pivoted to the plate 40 secured to the side of the pinion 41, both pinion and plate being freely 90 mounted on the shaft 35, on the step 40', while the steps 36' and 40' respectively receive the spur gear and pawl plate.

Motion is conveyed to the pinion 41 by 95 means of the rack 42 when pressure is applied to the button head 43 of the latter and the resistance of the return spring 44 overcome; the rack bar has a bearing in the cover plate (not shown) and also a foot bearing 45.

Whenever it may be desired to set all of the numeral wheels to their initial position the numeral wheel driving mechanism is disengaged and the button 43 depressed whereupon pinion 41 is caused to rotate, transmitting motion to the gear 36 through the pawl and ratchet wheel 37 which caused the gear 19 to revolve, acting to turn the plate 16 around the shaft 12, the projections 17 picking up the teeth 18 in the numeral 110 wheel gears 11 at any point where they may chance to be, moving them all into alinement

so that a row of like characters appear at the opening, where visual registration is obtained. Obviously the first effect of rotating the gear 19 is to raise the projections above the concentric surface of the sleeve 20 by reason of oscillating the lever 30 so as to cause it to leave the recess 29 and travel in an annular path one complete revolution around the interior of the washer 27. Upon releasing the button it will return to its original normal position at which time the lever 30 is in the depression 29 and the projection 17 removed out of engagement with the teeth 19 so that the gears and the numeral wheels can revolve as required for computation.

Having thus described my invention and the manner of its use, what I claim as new and desire to secure by Letters Patent is:—

20. 1. In a device of the class described, the combination with a plurality of independent indicating disks, of a fixed shaft, a sleeve rotatable on said shaft and on which said disks are revolvably mounted, a toothed member longitudinally disposed in a slot formed in said sleeve, means for engaging said toothed member with the interior of said disks, means for turning them to a predetermined point uniformly and means for disengaging said disks when so turned, all of said means being combined with and dependent upon the rotation of said sleeve.
25. 2. In a device of the class described, the combination with a plurality of numeral disks and a housing therefor, of a shaft for said disks, a sleeve revolvably mounted thereon having a longitudinal groove therethrough, a pawl plate carried in said groove pivoted at each end near the edge, a plurality of projections, corresponding to the numeral disks formed upon its outer opposite edge, means for causing said projections to engage internally with the numeral disks and means combined therewith whereby said disks may be rotated to a uniform position relative to the numerals thereon.
30. 3. In a device of the class described, the combination with a shaft, a sleeve rotatable thereon, a frame therefor and a plurality of numeral disks mounted on said sleeve, of a

plate fitted in a longitudinal slot in said sleeve and pivoted to oscillate in the slot, a lever attached to said plate at one end thereof, a spring adapted to force said plate inwardly, a cam set in the frame engaging said lever adapted to force said plate outwardly, a projection in a recessed portion of said disks, engaging means combined with said plate for intercepting said projections whereby they may be turned to register a uniform row of numerals, and means for actuating said plate.

4. In a device of the class described, the combination with a shaft and a plurality of numeral disks mounted thereon, of a sleeve intermediate of said shaft and said disks, a plate set in a groove formed longitudinally in said sleeve, means for causing said plate to engage with projections in said disks upon rotating the plate, said means constituting a lock for holding the plate out of engagement except when re-setting said disks and a rack and pinion mechanism for operating said plate.

5. In a device of the class described, the combination with a plurality of independently, rotatable indicating disks, of a tooth formed in an annular recess in each of said disks concentric with their bore, a sleeve upon which said disks are freely mounted to turn in either direction, said sleeve having a longitudinal opening, a shaft within said sleeve, a curved plate pivotally disposed in said opening, a gear at one end of said shaft, connections between said plate and said gear whereby the plate may be revolved around the shaft, a lever attached to the other end of said plate, an internal cam operatively engaging said lever whereby said plate may be raised from said shaft and caused to engage with the teeth formed in the disks, and means for revolving said gear whereby the numeral disks are revolved.

In testimony whereof I have signed my name to this specification in the presence of two subscribing witnesses.

HART E. DELVIN.
